Patented Sept. 20, 1960

188,878

MASTER VALVE FOR STOVES OR THE LIKE

Lewis R. Kinsey, 108 S. 25th St., Phoenix, Ariz.

Filed Nov. 21, 1958, Ser. No. 53,464

Term of patent 14 years

(Cl. D78—1)

Fig. 2

Fig. 1

Fig. 4

Fig. 3

Figure 1 is a side elevation of a master valve for stoves or the like showing my new design.

Figure 2 is a top plan view thereof.

Figure 3 is a bottom plan view thereof.

Figure 4 is an elevation thereof as seen from the right of Figure 1.

I claim:

The ornamental design for a master valve for stoves or the like, as shown.
